UNITED STATES PATENT OFFICE.

BERNARD E. LOEPPER, OF PHILADELPHIA, PENNSYLVANIA.

DESIGN FOR A CHARM.

42,768.

Specification for Design.

Patented July 9, 1912.

Application filed March 27, 1912. Serial No. 686,628. Term of patent 7 years.

To all whom it may concern:

Be it known that I, BERNARD E. LOEPPER, a citizen of the United States, residing at No. 112 South Eleventh street, in the city of Philadelphia, in the county of Philadelphia and State of Pennsylvania, have invented a new, original, and ornamental Design for a Charm, of which the following is a specification, reference being had to the accompanying drawing, forming part thereof.

Figure 1 is a plan view of the obverse side of my design and Fig. 2 is a similar view of the reverse side thereof.

I claim:

The ornamental design for a charm, as shown.

BERNARD E. LOEPPER.
